UNITED STATES PATENT OFFICE

ELMER L. BALLEW, OF CHICAGO, ILLINOIS

PORTABLE MOVING RACING APPARATUS

Application filed September 27, 1928. Serial No. 308,738.

This invention relates to certain novel improvements in portable moving racing apparatus, and has for its principal object the provision of an improved construction of this character which will be highly efficient in use and economical in manufacture.

It is among the objects of my invention to provide a device of the above named character which will be arranged in such a manner that it may be easily transported and expeditiously set up.

Another object of the invention is to provide a device of the above named character which will be particularly adapted for use in connection with so called dog racing and consists in providing a trackway having a starting and finishing point associated therewith.

Another object of the invention is to arrange the trackway in such a manner that the floor thereof may be moved in a direction opposite to the travel of the dogs or the like thereover.

A still further object of the invention is to provide a mechanism of the above named type which will be arranged such that the devices may be disposed so as to provide a course of any desired length.

A still further object of the invention is to arrange a device of the above named character in such a manner that a lure may be associated therewith and to arrange the device such that this lure will be caused to disappear at a desired time.

35 A still further object of the invention is to provide a device of the above named character which will have associated therewith a starting box of an improved design such that the dogs may all be released at the same time.

40 A still further object of the invention is to arrange a device of the above named character in such a manner that it will embody a moving floor that may be driven by the
45 tread of the dogs thereacross or which may be driven by a suitable source of power.

be driven. Other objects will appear hereinafter. The invention consists in the novel combination and arrangement of parts to be 50 hereinafter described and claimed.

The invention will be best understood by reference to the accompanying drawings, showing the preferred form of construction and in which;

Fig. 1 is a side view depicting a preferred form of construction for my device; 55

Fig. 2 is a fragmental plan view of the device illustrated in Fig. 1;

Fig. 3 is a fragmental plan view depicting the lure and the mounting therefor; Fig. 4 is a side view of a preferred form of a starting box adapted to be associated with the device.

Fig. 5 is a view depicting another form of starting box for the device; 65

Fig. 6 is a plan view, partly in elevation and partly in section, of the device as illustrated in Fig. 5; and

Fig. 7 is a detail view depicting a modified form of construction for my device. 70

In the drawings I depict a device which is particularly adapted for the racing of dogs and it is to be understood that by making certain modifications which will be readily apparent to any one skilled in the art, the

apparent to any one skilled in the art, the device might be adapted for other purposes and this is intended to be within the purview of my invention. In the accompanying drawings I depict a device which includes a starting point 10, a track 11, and a finish-
80

a starting point 11, a running point 12. In the present instance I depict these three as being closely associated together but it is to be understood that the starting point might be positioned at a point remote from the track portion 11 and the 85

finishing point might also be arranged in this manner and the track 11 might be composed of any number of movable track portions such as are generically indicated by 25 in the drawing. It is to be understood

13 in the drawings. It is to be understood that the movable track portions 13 would be arranged in this latter instance in successive relation. 90

In the present instance the movable track section 13 embodies a frame 14 which has cross members 15, 16, 17, and 18 associated therewith. In the present instance at the points of inter-section between the cross braces 15 and 16 and members 15 and 18 I journal shafts 19 and 20. Mounted upon

the shafts 19 and 20 are, in the present instance, a plurality of drum members 21. These drum members 21 are arranged so as to be of a width sufficient to provide a path along which the dogs may run, it being understood that the term dogs is used herein in a generic sense. It is to be understood, however, that if desired the shaft 19 might be arranged so as to support but a single drum and a similar construction might be provided in association with the shaft 20.

In the cross braces 17 I provide vertically extending slots 22. The end portions of the shaft 23 are disposed in these slots 22.

Drums 24 substantially similar to the drums 21 are associated with the shaft 23, it being understood that while in the present instance I show a plurality of drums 24 it is within the purview of my invention to provide but a single drum on this shaft as described in connection with the shafts 19 and 20. Directed around the drums 21 and 24 is an endless belt structure indicated by 25. In the present instance this endless belt structure embodies a plurality of belt members 26 which are associated with each set of the drums 21 and 24. In the present instance the belt member 25 is formed from a suitable material such as, for example, a fabric so as to form a structure substantially similar to a belt. However, it is to be understood that the belt might be formed from a plurality of suitably inter-connected sections without departing from the purview of my invention. In the present instance the peripheries of the drums 21 and 24 are made smooth but it is to be understood that these peripheries might be corrugated without departing from the purview of my invention. Further, in the event the endless belt structure 25 was formed from a plurality of sections suitably joined together, the peripheries of these drums might be arranged so as to co-operate with these sections.

In a construction wherein a plurality of belt sections 26 are provided it is necessary that the space therebetween be arranged such that the dogs may not get between the said belt members 26. This may be accomplished by extending between the end portions of the frame 14 suitable covering members 26'. In place of the covering members 26' it is readily apparent that partitions might be provided between the various belt sections 26 so as to confine a dog on each of said belt sections and such a partition is indicated by 27 in the drawing wherein said partition is indicated by dotted lines in Fig. 1.

It is to be understood, however, that in the event but a single belt section is used these partitions and these covering members might be dispensed with since all the dogs would run upon the same surface.

Extending between the members 15 and

between opposite sides of the frame 14 is a shaft 28. Mounted at suitable points on this shaft are spring members 29 which have corresponding end portions thereof pivotally connected to the shaft 28. The opposite end portions of the members 29 indicated by 30 are arranged so as to extend across above the shaft 23. Carried by the cross-braces 15 is a cross-brace 31. Extending downwardly from the cross-brace 31 is a stationary portion 32 of a jack screw structure. The movable portion 33 of the jack screw structure is connected to the portion 30 and the screw 34 is arranged between the portions 32 and 33 and is manipulated through the medium of a handle structure 35. The screw 34 is arranged so as to dispose the portion 33 in such a manner that the portion 30 will be caused to bear against the shaft 23 and in this manner the belt member 25 may be placed under suitable tension.

The portion of the belt 25 extending between the drums 21 and carried by the shafts 19 and 20 is the portion which is adapted to provide the trackway and this portion is indicated by 36 in the drawings. Arranged below the portion 36 and suitably carried by the frame 14 are a plurality of roller members 37 which are adapted to form a substantial surface below the portion 36 and thus provide a relatively solid trackway. As the dogs pass over the portion 36 the action of their feet thereon will tend to move the endless belt structure 25 in a direction toward the shaft 19. It is therefore apparent that the progress of the dogs across the portion 36 will be greatly retarded and therefore a race of relatively great length may be run in a comparatively short space. If desired, power may be supplied to one of the shafts supporting the drums which carry the endless belt structure 25. When this construction is employed the endless belt structure 25 may be driven in a direction toward the shaft 19 and it is apparent will operate the belt independent of the action of the dogs. When this latter structure is employed the belt is preferably driven at a speed less than the forward speed of the dogs in order that they will gradually move from the starting point 10 to the finishing point 12.

Extending from one edge of the frame 14 to a point substantially in vertical alignment with the shaft 19 is a floor portion 38. A similar floor portion 39 extends between the frame 14 and a point in alignment with the shaft 20. It is therefore apparent that when a plurality of the devices 13 are to be arranged in alignment so as to provide a relatively great distance between the starting point 10 and the finishing point 12 that between these various members 13 there will

be a stationary floor space comprised of the abutting members 38 and 39.

Adjacent the last of the floor portions 39 I arrange a stationary floor portion 40 which comprises a portion of the finishing point 12. The lure indicated by 41 is arranged above this floor 40 and in the present instance is carried on a shaft 42 that extends to the pivotally mounted member

43. This lure is normally disposed so as to be in view of the dogs passing over the section 11 so as to serve to attract them. In the present instance a hurdle 44 is supported above the floor 40 in such a manner as to

provide a space 45 between the lower edge of the hurdle and the floor 40. When it is desired to terminate the race the member 43 is rotated about the pivotal support 46 therefore and the lure 41 is passed through

the opening 45. The dogs arriving on the portion 40 and seeing the lure disappear behind the hurdle 44 leap the hurdle and proceed toward the finishing point which is indicated by the upright member 47. A

suitable screen or other vision preventing device may be associated with this member 47 and after the dogs pass therebehind they are caught. The particular finishing point may be arranged on the portion 40 either before or behind the hurdle 44 or the hurdle 44 may serve as the finishing point.

In the present instance I show the starting boxes which are generically indicated by 48 as being closely associated with the member 38 but it is to be understood that a stationary floor space might be provided between the starting boxes 48 and the member 38 and still be within the purview of my invention.

In Fig. 4 I have illustrated one form of starting box 48 which includes a housing 50 having an exit opening 51 at one end thereof which is normally closed by door 52. The door 52 is supported in position by arms 53 and 54 and terminate in a bearing portion 55 that is pivotally mounted as indicated at 56. A handle portion 57 extends outwardly from the bearing portion 55 and by moving the handle portion 57 from the full line position of Fig. 4 into the dotted line position of this figure the door 52 is moved from closing position with respect to the opening 51. It is apparent that when such a structure is used for the starting boxes 48 all of the handles 57 will be manipulated at the same time and thus the dogs will rush out of the starting boxes toward the trackway 11, the dogs being attracted by the lure 41. In Figs. 5 and 6 I have depicted an

other type of starting box which comprises a plurality of housings 58 which have exit openings 59 at one end thereof and are normally closed by door members 60. The door members 60 have one of the edges thereof secured to the shafts 61 that are suitably

supported in the housing 58. On the shafts 61 are worm wheels 62 that mesh with the worm gear 63 mounted on the shaft 64. At one end of the device the shaft 64 is provided with the gear 65 that meshes with the gear 66 and is rotatably mounted as indicated at 67. A handle portion 68 is provided and when this handle portion 68 is manipulated the gear 66 is revolved and this revolves the gear 65 that in turn imparts rotation to the shaft 64. This rotates the worm gears 63 which operate the worm wheels 62 to move the shafts 61 such that the door members 60 are moved from closing position.

In Fig. 7 I have depicted one modified form of construction for the device 13 over that illustrated in Figs. 1 and 2. Herein the belt structure 25 is directed around a drum construction consisting of 4 drums 69 that are mounted so as to form a shape substantially similar, in this instance, to a rectangle. The portion extending between the upwardly disposed rollers 69 provides the trackway. This modification is depicted in order to illustrate that the device 13 might be arranged in a number of different manners so as to provide a moving surface over which the dogs may run.

It is apparent from the foregoing description that I have provided a device which is comprised of units that may be readily disassembled so as to facilitate transportation. The device is also arranged such that it is flexible in that it may be arranged in a number of different embodiments. The construction is such that the device may be set up either above the ground or imbedded therein and if desired the device might be used interiorly of a building in order that the racing might continue in inclement weather. While I have described two forms of starting boxes which may be used with my device it is to be understood that other types might be used without departing from the purview of my invention and further example of this is that the starting boxes might be arranged so as to be bottomless and in order to start the race these boxes might be elevated through the usage of a suitable block and tackle or the like and it is obvious that in the event such boxes were raised the dogs would be released.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variation and modifications as come within the scope of the appended claims.

Having thus described my invention what I claim is new and desire to protect by Letters Patent is:

1. In a racing device, a starting point, a finishing point, a track portion arranged between said starting point and said finishing point embodying a movable floor, a lure arranged adjacent said finishing point, and means for moving said lure from operating position. 70
2. In a racing device, a starting point, a finishing point, a track portion arranged between said starting point and said finishing point embodying a movable floor, a lure arranged adjacent said finishing point, and means for moving said lure from operating position, a hurdle arranged at said finishing point, said lure being moved past said hurdle whereby to conceal said lure from position. 75
3. In a racing device, a starting point, a finishing point, a track portion arranged between said starting and finishing points embodying a belt like member providing a floor, means disposed below the portion of said belt like member extended between said starting and finishing points for supporting the same, means for imparting movement to said belt like member whereby the portion thereof extended between said starting and finishing points may be moved in the direction toward said starting point, and a lure disposed adjacent said finishing point. 80
4. In a racing device, a starting point, a finishing point, a track portion arranged between said starting and finishing points embodying a belt like member providing a floor, means disposed below the portion of said belt like member extended between said starting and finishing points for supporting the same, means for imparting movement to said belt like member whereby the portion thereof extended between said starting and finishing points may be moved in the direction toward said starting point, a lure disposed adjacent said finishing point, and means for moving said lure to permit said lure to be concealed at desired times. 85
5. In racing apparatus, a supporting structure, drums rotatably mounted in said supporting structure, an endless belt movable around said drums and defining a floor between the starting and finishing points of a race run thereon, certain of said drums being mounted for vertical movement in said supporting structure, yieldable means carried by said supporting structure normally urging said vertically movable drums toward said belt and in a direction away from said floor, and adjustable means for varying tension of said yieldable means and said belt. 90
6. A portable racing apparatus comprising an endless belt providing a movable floor adapted to travel between the starting and finishing points of a race, a supporting structure for said belt including a stationary frame and rotatable means around which said belt is directed in said frame, said rotatable means including drums mounted for 95
- vertical movement in said frame, means for urging said drums toward said belt in a direction away from said floor including yieldable arms pivotally carried by said frame, and adjustable means for tensioning said arms and said belt. 100
7. A portable racing apparatus comprising an endless belt providing a movable floor adapted to travel between the starting and finishing points of a race, a supporting structure for said belt including a stationary frame and rotatable means around which said belt is directed in said frame, said rotatable means including drums mounted for vertical movement in said frame, means for urging said drums toward said belt in a direction away from said floor including yieldable arms pivotally carried by said frame, and adjustable means for tensioning said arms and said belt, said adjustable means including screw members carried by said frame and engaged with the free ends of said arms. 105
- In testimony whereof I affix my signature. 110
